Fig. 1.

Fig. 2.

Fig. 3.

FIGURE 1 is a side elevational view of a combined base plate and solar cell for a solar radiation measuring device, showing my new design;

FIGURE 2 is a top plan view thereof; and

FIGURE 3 is a bottom plan view thereof.

The broken lines disclosed on the drawing are shown for illustrative purposes only.

The undisclosed sides of the solar cell are substantially the same in appearance as the side shown.

The top of the base plate is unornamented except for a conventional opening.

I claim:

The ornamental design for a combined base plate and solar cell for a solar radiation measuring device, as shown and described.
